JEREMIAH DEPUE, OF CALIFORNIA, MICHIGAN.

Letters Patent No. 76,061, dated March 31, 1868.

IMPROVEMENT IN COMBINED FEED-TROUGH AND RACK.

The Schedule referred to in these Letters Patent and making part of the same.

TO ALL WHOM IT MAY CONCERN:

Be it known that I, JEREMIAH DEPUE, of California, Branch county, Michigan, have invented a new and improved "Combined Feed-Trough and Rack" for the feeding of sheep and other stock; and I do declare that the following is a full and exact description thereof, reference being had to the accompanying drawings, and to the letters of reference marked thereon.

First, the rack may be of any desired length, and a special weight and thickness of material not required. The improvement over other racks consists in the convenient and sure method of keeping the food (both hay and grain) dry, and the easy method of adjusting the rack for either sheep or cattle and horses.

Figure No. 1 represents the rack with the roof on. The end-pieces E are made close, and the upper end sloped or gabled, for the support of the roof A A, which is further supported by the board D, forming the upper part of the rack proper. The roof is also kept in its place by means of slats, as seen by L L, in Figure 2, and by hooks at the ends and middle, as seen at g g g, in Fig. No. 1.

The feed-box, for feeding grain or chopped feed, is represented by K. It is sheltered from the rains by the projecting roof A A, and seed and dust from the hay-rack H are prevented from falling into it by means of the lid B, which being raised, fits closely to the board D, and is fastened by a button at f.

To convert this into a rack for feeding horses or cattle, take each side of the roof A A from the top, and, turning the boards once over, place them in the supports C C, as represented in fig. 2. These supports are sufficiently long and firm to hold the boards securely to the sides of the rack, thus preventing the feed-boxes from being pawed and injured by the horses and cattle while feeding.

What I claim as my invention, and desire to secure by Letters Patent, is—

The feed-box K and rack H, in combination with the roof A, slats C, button f, and board D, arranged substantially as herein shown and described, for the purpose set forth.

JEREMIAH DEPUE.
